(57) **CLAIM**

The ornamental design for a beverage container cover as shown and described.

DESCRIPTION

FIG. 1 is a perspective view of a beverage container cover. FIG. 2 is a front view of the beverage container cover of FIG. 1.

FIG. 3 is a rear view of the beverage container cover of FIG. 1.

FIG. 4 is a left side view of the beverage container cover of FIG. 1.

FIG. 5 is a right-side view of the beverage container cover of FIG. 1.

FIG. 6 is a bottom view of the beverage container cover of FIG. 1; and,

FIG. 7 is a top view of the beverage container cover of FIG. 1.

The broken lines in the drawings depict portions of the beverage container cover that form no part of the claimed design.

1 Claim, 7 Drawing Sheets
